DESIGN FOR A BATHROOM STOOL

George B. Bentz, New York, N. Y.

Application September 23, 1937, Serial No. 71,764

Term of patent 14 years

To all whom it may concern:

Be it known that I, George B. Bentz, a citizen of the United States, residing at New York, in the county and State of New York, have invented a new, original, and ornamental Design for Bathroom Stools, of which the following is a specification, reference being had to the accompanying drawing, forming part thereof.

Fig. 1 is a perspective view of a bathroom stool showing my new design.

Fig. 2 is a side elevation.

Fig. 3 is a side elevation at right angles to Figure 2.

I claim:—

The ornamental design for a bathroom stool, as shown.

GEORGE B. BENTZ.
